CHARLES H. FOSTER, OF SAN FRANCISCO, CALIFORNIA.

Letters Patent No. 96,414, dated November 2, 1869.

IMPROVED BUT-HINGE.

The Schedule referred to in these Letters Patent and making part of the same.

To all whom it may concern:

Be it known that I, CHARLES H. FOSTER, of the city and county of San Francisco, State of California, have invented Improvements in Door-Buts and Marine-Hinges; and I do hereby declare the following description and accompanying drawings are sufficient to enable any person skilled in the art or science to which it most nearly appertains, to make and use my said invention or improvements, without further invention or experiment.

The nature of my invention and improvements in hinges consists in the application, in an ordinary iron but, of a brass bushing in the socket of the hinge and a brass pintle to prevent the socket from rusting and adhering to the pintle of the hinge.

As is the stationary side of an iron but or hinge, upon which doors are hung.

In the place of the iron pintles commonly used, I use a pintle, C, made of brass or other non-corrosive metal, and secured by any means in the proper position on the but.

The socket D, in the swinging side of the iron hinge, and inside of which the pintle C works, is bushed with a similar metal, as shown, thus forming

a non-corrosive bearing upon which the door will hang.

Buts are made entirely of brass for marine purposes, but their cost is much greater than iron ones.

By constructing buts in the manner above described, I secure all the advantages of the brass but, while I reduce the cost almost to that of an ordinary iron but.

The leaves or iron portion of the but being painted, preserves them from the action of the water, which destroys the pintle.

Having thus described my invention,

What I claim, and desire to secure by Letters Patent, is—

The application, in an ordinary iron but, of the brass bushing in the socket D, and brass pintle C, of the hinge, to prevent the socket from rusting and adhering to the pintle of the hinge.

In witness whereof, I have hereunto set my hand and seal.

CHARLES H. FOSTER. [L. S.]
